UNITED STATES PATENT OFFICE.

JOHN EDWARD WRIGHT, OF PITTSBURGH, PENNSYLVANIA, ASSIGNOR TO WRIGHT TELEGRAPHIC TYPEWRITER COMPANY, OF NEW YORK, N. Y., A CORPORATION OF DELAWARE.

KEYBOARD FOR PRINTING-TELEGRAPH SYSTEMS.

1,090,366.

Specification of Letters Patent. Patented Mar. 17, 1914.

Application filed January 22, 1913. Serial No. 743,510.

To all whom it may concern:

Be it known that I, JOHN E. WRIGHT, a citizen of the United States, residing at Pittsburgh, county of Allegheny, and State

5 of Pennsylvania, have invented certain new and useful Improvements in Keyboards for Printing-Telegraph Systems, of which the following is a full, clear, and exact description.

10 My present invention is an improvement in keyboards for printing telegraph systems, that is to say, apparatus comprising a bank of keys, by the successive depression of which mechanism is set in operation by

15 which current impulses or series of impulses corresponding to the keys depressed, are sent to line to effect the operation of a receiver, which may be a perforator, a printer or an indicator of any suitable character.

20 In the particular system for which this device was designed, I employ a column printing telegraph instrument in which the selection and printing of characters, spacing, paper feed and such other functions as are

25 involved in the operation of that instrument, are effected by means of electromagnetically controlled devices, each having a special function and connected up with a plurality of circuits local to the instrument, in such

30 manner that each particular operation, or series of certain operations, results from the completion of a corresponding local circuit, or the simultaneous completion of two or more of such circuits. This receiving instru-

35 ment I have made the subject of an application filed by me on December 9, 1912, Ser. No. 735,682.

In order to reduce the number of line or transmission circuits to a minimum, that is 40 a single wire, I employ in connection with such a receiver, an apparatus which is placed intermediate to the same and the line, and which contains a plurality of circuits corresponding to, and designed to control, those

45 of the said receiver, and a plurality of circuits, as few in number as practical working conditions will permit, which are designed to be controlled by currents transmitted over the line and by means of which that one of a

50 number of circuit closers is selected which, when operated, completes the receiver circuit and prints the character or effects the operation corresponding to the impulse or combination of impulses constituting the 55 signal transmitted over the line. This ap-

paratus, which I define as a translator, forms the subject of an application for patent filed by me of even date herewith, Serial No. 743,511.

As the translator contains a plurality of 60 line controlled circuits local to itself, and as the transmission of currents is effected by means of a single circuit or line wire, I employ in connection with such translator an apparatus for distributing to its appropriate 65 circuits the impulses sent over the line, and to otherwise control its operation. This apparatus comprises a sunflower or distributor ring, the segments of which are connected with the controlled circuits of the translator, 70 and a corresponding sunflower instrument at the sending end of the line, into the segments of which impulses, constituting or corresponding to those to be transmitted over the line, are sent by a suitable device. 75 The apparatus comprising the two sunflower rings with the means for controlling their operation, forms the subject of an application for patent filed by me of even date here- 80 with, Serial No. 743,512.

To complete the system some means must be employed in connection with the sunflower transmitting device to properly control its operation, and to direct through its appropriate segments, the current impulses 85 that are to determine the operation of the receiver, and for this purpose I have devised the keyboard instrument upon which is based my present application.

The main purpose of the device in question, is to close, by the depression of single keys, one or more or all of the circuits leading to the segments of the transmitting sunflower; by the same operation to start the latter in action and by means of suitable 95 mechanism, which establishes reciprocal relations between the key board and the transmitting instrument, to control the operation of the former and to lock the keys to prevent their operation until the signal corresponding to the key depressed has been completed. The improvements therefore reside in the means for accomplishing these results, and will be described by reference to the accompanying drawings:

Figure 1 is a top plan view of the complete key board instrument. Fig. 2 is a plan view of those working parts which are exposed by the removal of the top plate or superstructure. Fig. 3 is a central vertical 110

cross section of the instrument shown in Fig. 1. Fig. 4 is an end view of the device with the side plates removed. Fig. 5 is a view in elevation of a detail of mechanism. Fig. 5 6 is a central section at right angles to the plane of Fig. 2. Fig. 7 is a detail in elevation and part section of one of a series of circuit closing devices. Fig. 8 is a diagram of the circuit connections of the key board 10 and the instruments employed therewith at the home or sending station.

In the general mechanical design of the instrument I have followed that heretofore adopted by me and which resembles that of an ordinary typewriter, having a cast iron base 1, with a projecting front 2, containing and exposing through an opening in its top, a bank of keys similar to those commonly employed in single case machines, and a raised platform 3, supported by the side plates. The key levers 4 contain notches at their rear ends to receive the knife edge of a stationary bar 5, and rest upon a rod 6. They are normally held in raised position and against the knife edge by spiral springs 7. The main keys correspond to letters, numerals and other characters on the type wheel of a receiver, while certain other keys are employed for spacing, for returning the type wheel carriage from any point in its line of travel to its initial position, and at the same time feeding the paper one line space, or for feeding the paper without returning the carriage, and for other purposes, as will be more fully described hereinafter.

Immediately beneath the series of key levers 4 is a bar 8, carried by arms secured to a rock shaft 9 and held normally up against the levers by a spiral spring 10, connected to a rigid arm projecting from said rock shaft. Another rigid arm 11, extending from this shaft, is connected by a wire or rod 12, see Figs. 3 and 4, with a circuit controlling lever 13 mounted on the platform 3 and normally out of contact with its stop. On the depression of any key, this circuit controller, through the described connections, is operated to complete a circuit which, as will 50 more fully hereinafter appear, is intended to release and start in operation the sunflower through which the impulses determined by the further operation of the levers, are to be sent to line. Another bar 14, 55 carried by arms 15, rigid with a rock shaft 16, extends across the instrument beneath the series of key levers, and is held in a normally elevated position by a spiral spring 17 acting upon said shaft. This bar has a 60 series of projections 18 lying under some of the levers, but not under others, so that it will be depressed by those key levers only which encounter the projections thereon. When so depressed the bar draws down 65 against the force of a spring 20, the ends

19 of a bell crank lever with which it is connected by a rod 21, and effects an adjustment of mechanism which will be hereinafter described, whereby a special magnet in the receiver known as the shift magnet 70 will be operated. It is sufficient, for the present, to say that every key lever, with the single exception of one which lies over one of the projections on bar 14, is connected by a rod 22 with a pivoted bell crank lever 23, Fig. 6, and when depressed draws down the forward end of said lever against the force of a spiral spring 24. The other end of each bell crank lever 23 is pivotally connected with a slide bar 25 adapted to reciprocate in suitable guides in the frame of the instrument over a series of five rock shafts 26, and provided with one or more stops or lugs 27, in the path of which, when present, extend arms 28 rigid with the rock shafts 26. The disposition of the lugs 27 is such that by the depression of any given key, one or more or all of the rock shafts in different permutations and combinations will be turned by the engagement of lugs 80 27 and the arms 28.

On the top plate or platform 3, see Figs. 1 and 3, is mounted an electromagnet 29 with plunger armatures 30 joined by a yoke 31 which is secured to the end bar or plate of a rectangular frame 32, mounted to reciprocate in the axial plane of the magnet against the force of a spiral spring 33. The front bar or plate of this frame 32 carries six parallel rods 34, the forward ends of which extend through guide openings in a stationary plate or bar 35, and the other ends of which are free to slide through the end plate of frame 32, but are surrounded by light spiral springs 36 interposed between said end plate and collars 37 fixed to the rods 34 and acting to maintain said rods in their forward position. Any other construction which supports the rods on spring seats with reference to the frame 32 may be adopted.

By referring now to Fig. 4, it will be seen that the arm 38 of the bell crank lever, the arm 19 of which is connected with the bar 14, lies normally in the path of one of the rods 34, and arms 39, fixed to the rock shafts 26, lie normally in the paths of the remainder of said rods, so that, assuming the magnet 29 to be energized and the frame 32 to be shifted thereby, the rods 34 encountering the said arms 38 and 39 will be forced backward against the force of springs 36, through their seats in frame 32, their position with respect to the other parts of the instrument not being materially altered.

Six levers 40, with double contact points 41, are pivoted to an insulating base 42, between two sets of stationary contacts 43 and 44, and are normally held in engagement with the latter by spiral springs 45. 130

The rods 34 extend through openings in the levers 40, and when the frame 32 is shifted by the action of magnet 29, the collars 37 on the rods, if the latter be not intercepted by the arms 38 or 39, will engage the said levers, forcing them out of contact with stops 44 and into contact with stops 43. Under normal conditions a small space intervenes between the collars 37 and levers 10, to permit a certain forward movement of rods 34 before this engagement is established.

The contacts 43 are fixed in an insulating plate 46, and form terminals of independent 15 circuits, while contacts 44 are supported by a conducting plate or bar 47 for the purposes to be explained.

Each of the key levers 4 has a depending plate 48, see Figs. 3, 4 and 6, with a 20 notch 49 in its edge and a beveled end 50. Immediately beneath this series of notched plates 48 is a bar 51 carried by arms 52 secured to a rock shaft 53 mounted in the side plates of the instrument. An electromagnet 25 or solenoid 54 mounted beneath the working parts of the device and which, as shown in Fig. 2, is provided with cores 55 carried by a yoke 56 and operating against a spiral spring 57, operates, when energized, to rock the shaft 53 by means of a connecting rod 58 pivotally joined to the yoke and to one of the arms 52 respectively.

The purpose and function of the mechanical and electromagnetic elements thus described will be more fully understood by the following statement of operation, in connection with which reference will be made to the diagram of circuit connections, Fig. 8. In this diagram, the terminals of the 40 sending sunflower, to correspond with those of the sending sunflower in my application Serial No. 743,512, are designated by the letters A to L inclusive. This diagram illustrates, conventionally, the apparatus at the 45 sending or home station of the system and the circuit connections employed when the several instruments are arranged for duplex operation. This being, for the moment, assumed, let it be further assumed that some 50 one of the key levers be depressed to send over the line the signal corresponding thereto. The first result following the depression of the key and its lever 4 will be to force down the bar 8, which, as has been 55 explained, is common to all of the key levers, thereby turning the rock shaft 9 and operating the circuit controller 13. This disconnects a local battery 59 from ground through a condenser 70 and connects the 60 condenser with the terminal J of the sending sunflower 60 that includes in its circuit the magnet 61, the function of which is to release the shaft of that instrument, permitting it to start in rotation. As the 65 current impulse which effects this operation

is the condenser discharge, it is of very short duration, and the release magnet 61 being but momentarily energized, restores the locking devices so quickly that the sunflower shaft, after making a single revolution, will be again locked against rotation. The depression of the key in question, also depresses the bell crank lever 23 connected therewith, and draws forward the corresponding slide bar 25. This bar carries one or more lugs 27, which therefore will operate to rock one or more of the shafts 26 and swing the corresponding arms 39 out of the paths of the rods 34, and thus that particular combination or permutation which corresponds to the signal to be sent is established. But in the meantime, by the rotation of the sunflower shaft, a cam 62 thereon has operated a circuit-controller 63 which completes a circuit from the battery 59 through the contact magnet 29, which, being energized, shifts the frame 32 carrying the rods 34. Of these latter, those only which find a clear path resulting from the withdrawal of arms 39, will travel forward with the frame, and in so doing shift the corresponding levers 40 out of contact with their stops 44 and into contact with the opposing insulated stops 43. If we assume, for sake of illustration, that the contacts thus operated are those marked *a* and *b* in Fig. 8, that is the second and fourth, counting from the lower end of the series shown in the diagram, and follow the connections illustrated, we will find that the local battery 64, which is normally grounded through one side of the double polarized transmitting relay 65 by means of segment 66^a of the sunflower 60, upon which the arm 67 of that instrument normally bears, and which is also connected to each of the other segments of the sunflower through the same side of the relay by the levers 40 and the stops 44, upon which the latter normally rest, is, by the operation referred to, connected through the other side of said relay by the levers 40 and stops 43 of the circuit controllers *a* and *b* to segments 68 and 69 of the sunflower. Another operation immediately following the release of the sunflower shaft, and hence the depression of a key lever, is effected by a cam 71 on the sunflower shaft that operates a circuit closer 72, which connects the local battery 59 to ground through the lock magnet 54 in the key board instrument. This shifts the arms 52 and brings the bar 51 into the notch 49 of the key that has been depressed, and against the beveled ends 50 of the plates 48 of all of the other keys, thus preventing the depressed keys from rising and the raised keys from being depressed. These conditions having been established, persist as long as the circuit controllers 63 and 72 are maintained in operation by their 130

respective cams, or, in other words, until the sunflower has practically completed one revolution. The further operations during that interval are effected by the sunflower and are as follows: The arm 67 passing from the first segment 66^a, breaks the ground connection of battery 64 through the right hand side of the transmitting relay. On reaching the next segment 73 the battery 64 is 5 grounded through the left side of the relay and an actuating impulse is sent to line by the relay, which, arriving at the other end of the line through a relay corresponding to the receiving relay 74 at the home station, finds a path through segment 75 of the corresponding receiving sunflower 80, upon 10 which segment the arm 76 of that instrument normally rests, and energizes during the interval of such contact, the release magnet corresponding to that designated by the numeral 77 of the receiving sunflower at the sending station. The transmitting sunflower at the home, and the receiving sunflower at the distant stations, are by this means set 15 in operation, and each will complete a revolution in the same interval of time.

It having been assumed that connections are established by the key board from battery 64 through the left side of the transmitting relay 65 to segments 68 and 69, it 20 follows that in its passage over these segments the arm 67 will ground these connections successively and thus send two marking impulses to line by the operation of the relay which will be received through the corresponding segments of the distant receiving sunflower. These currents will produce in the receiving translator controlled by the latter the same effect as the original 25 impulses produced in the home translator, those magnets 66 of which, as previously stated, corresponding to segments 68 and 69 of the transmitting sunflower being energized by the rotation of the arm 67 over the same. In passing over the other segment 30 of the sunflower ring, the arm 67 grounds the battery 64 through the right hand side of the relay 65, which results in the sending of reversed currents to line that have no other function than that of clearing the line.

It may be remarked that circuit controlling cams 78 on the shafts of the sunflower instruments at both stations are employed 35 to operate, at the proper instants of time, the release or actuating magnets of the translators which these instruments respectively control.

From the above description the operation 40 of this apparatus for any desired combination or permutation of impulses which go to make up a given signal will be understood. One of the keys, however, as I have stated, has no corresponding lever 23 for operating 45 the rock shafts 26, but merely turns the rock

shaft 16 by encountering, when depressed, a projection 18 on the swinging bar 14. A certain number of the other levers, moreover, also effect, when depressed, the same movement of the rock shaft 16, in addition to the establishment of the combinations resulting from the selection and operation of the rock shafts 26, and it remains to explain the operation in such cases.

In the receiver, which is not illustrated 75 herein, but made the subject of another application filed Dec. 9, 1912, Serial No. 735,682 as heretofore stated, the type wheel is turned by suitable mechanism through one or more steps, each including two character spaces. 80 There is also employed a device controlled by a special circuit that shifts or advances the type wheel through one character space from its original position, or from any other to which it may be brought by the turning 85 mechanism, and said device in its operation is independent of the turning mechanism and may act simultaneously therewith. The magnet for controlling this device is known as the shift magnet, and when a character is 90 to be printed that is found in any odd numbered row on the type wheel, this magnet is energized, either alone or in addition to those which operate to turn the type wheel through steps embracing two character spaces. The 95 key for operating this shift magnet without imparting any other movement to the type wheel, may be any one of the key board which, as above stated, has for that purpose no corresponding lever 23, but merely 100 acts to depress the bar 14. When, therefore, such key, or any other key that turns the bar 14, is depressed, the lever 19 is drawn down and its arm 38 shifted out of the path of the corresponding rod 34, so that the 105 contacts *c*, Fig. 8, will be operated either alone, or in conjunction with, any or all of the others, as the case may be. A reference to the diagram shows that this contact stands in the same relation to the various components of the system as the other contacts, and that when selected and operated it completes a connection from battery 64 to the 110 left hand side of relay 65 to one of the segments, as 79, of the sunflower.

With the selecting devices described it is manifest that a large number of distinctive signals may be transmitted and utilized for the control of the various devices in the receiver which perform the operations of printing, spacing, paper feed, etc. which are necessary in such cases, and that the keys may be equal in number to the permissible permutations and combinations of the maximum number of impulses allotted to any signal. It is possible, therefore, to have a separate key for each character and for each operation involved in the proper control of the receiver.

In the description of the diagram, Fig. 8, 130

reference to certain parts and partially illustrated connections has been omitted, as to one skilled in the art these will be well understood. For example, the segments of the receiving sunflower 80 are assumed to be connected with the terminals 81, of the receiving translator, although these connections are not fully shown.

What I claim is:

- 10 1. In a key board for telegraph systems which comprise a transmitting sunflower instrument, the combination with a bank of keys, of means controlled by all of the keys for releasing the transmitting sunflower, key controlled circuit selectors and means controlled by the sunflower for connecting the selected circuits to their corresponding sunflower segments, as set forth.
- 15 2. In a key board for telegraph systems which comprise a transmitting sunflower instrument, the combination with a bank of keys, of a battery, a condenser in circuit therewith, a release magnet circuit for the sunflower, and a circuit controller adapted to be operated by all of the keys to discharge the condenser through the release magnet circuit when any key is depressed.
- 20 3. In a key board for sunflower transmitters, the combination, with a bank of keys, of a key controlled circuit common to all of the keys for releasing the sunflower, key controlled circuit selectors and contact devices controlled by the sunflower for connecting the selected circuits to the corresponding sunflower segments.
- 25 4. In a key board for sunflower transmitting instruments, the combination with a

bank of keys, of a source of current, circuits from the same to the segments of the sunflower, circuit controllers in said circuits, key controlled selecting devices for permitting or preventing the operation of the circuit controllers, and an electromagnet, dependent for operation upon the movement of the sunflower, for actuating those circuit controllers which, by the adjustment of the selecting devices, are free to operate.

5. In a telegraph key board instrument, the combination with a bank of keys, of a series of circuits, circuit controllers therein, selecting devices for permitting or preventing the operation of the circuit controllers and connected mechanically with the keys, and a selecting device adapted to be operated by the depression of certain of said keys simultaneously with the operation of the selecting devices connected therewith.

6. The selecting mechanism for key board circuits herein described, comprising in combination, a bank of keys, a series of oscillating contact levers and contact stops therefor, a reciprocating frame and spring seated rods carried thereby for engaging the contact levers and corresponding in number and position therewith, stop levers normally in the path of said rods, selective connections between said levers and the keys, and means for reciprocating the frame, as set forth.

In testimony whereof I affix my signature in the presence of two subscribing witnesses,

JOHN EDWARD WRIGHT.
